UNITED STATES PATENT OFFICE

RUBY LEFI, OF NEW YORK, N. Y.

DESIGN FOR A STOCKING

Application filed July 13, 1929. Serial No. 32,044. Term of patent 7 years.

To all whom it may concern:

Be it known that I, RUBY LEFI, a citizen of the United States, and a resident of the city of New York, borough of Manhattan, in the county of New York, and State of New York, have invented the new, original, and ornamental Design for Stockings, of which the following is a specification.

Reference is had to the accompanying drawing, forming part thereof, wherein

I claim:

The ornamental design for a stocking substantially as shown.

RUBY LEFI.
